UNITED STATES PATENT OFFICE.

JOHN A. V. SMITH, OF MANCHESTER, NEW HAMPSHIRE.

SPEEDER-FLIER.

SPECIFICATION forming part of Letters Patent No. 350,782, dated October 12, 1886.

Application filed April 4, 1884. Serial No. 126,657. (No model.)

To all whom it may concern:

Be it known that I, JOHN A. V. SMITH, of Manchester, county of Hillsborough, State of New Hampshire, have invented an Improvement 5 in Speeder-Fliers, of which the following description, in connection with the accompanying drawings, is a specification, like letters on the drawings representing like parts.

Heretofore in that class of speeder-fliers having their pressers connected with short shafts placed in bearings outside the pressers, and provided with a pin to be engaged by a notched sleeve or hub connected with a spiral spring, very considerable difficulty has been experienced in connecting the spring with the sleeve or hub and with the foot-piece at the lower end of the spring. In such fliers the spring has been brazed or soldered directly upon the end of the sleeve or hub, and upon the flat side 15 of the foot-piece, as illustrated in Figure 5 of the drawings herein, and so attached the spring under strain is very apt to be broken away from the hub and foot-piece.

My invention is designed to overcome these 25 difficulties; and to this end it consists in means for connecting and adjusting the spring of a presser, substantially as hereinafter particularly set forth and claimed.

Fig. 1 represents a speeder-flier embodying my present improvements; Fig. 2, an enlarged partial side elevation of Fig. 1, but partially broken out; Fig. 3, a section of Fig. 2 in the dotted line $x-x$; Fig. 4, a modified form of hub; and Fig. 5 represents a hub, foot-piece, 35 and connected spring as heretofore constructed and in use.

Referring first to Fig. 5, it will be seen that the wire at the upper and lower end of the spring a is cut to form a flat surface. One of 40 these flat surfaces is placed against the end of the hub b and the other against the upper side of the foot-piece c , in which condition the said parts are soldered together, leaving but a portion of each end coil held to the hub and foot-piece, and held as shown they are very liable 45 to be broken off.

In accordance with my invention, the sleeve or hub d and foot e , Figs. 1, 2, and 3, are each shaped to enable at least one entire coil of the 50 spring f to be engaged and held securely in place thereby. In Figs. 1 and 2 the hub d is

chambered, as at d' , (see Fig. 2,) to receive the end of the wire spring f , and so, also, the foot e is chambered, as shown at e' , to receive the lower end of the said spring, and the first coil 55 of each of said ends is then soldered thereon, the solder being shown at d^2 and e^2 in black. In this manner each end coil is held firmly all about, and the end coil cannot be knocked off or broken from its connection with the hub 60 and foot by a blow against the spring, as is frequently the case with the attachment of the spring to the foot and hub, as is shown in Fig. 5.

As a modification of my invention, the hub may be reduced externally and prolonged, as 65 in Fig. 4, to enable the spring to surround it, rather than, as in Fig. 2, to let the hub surround the spring, the hub shown in Fig. 4 being the converse in construction but the equivalent in operation of the hub shown in Fig. 2. 70 The strength exerted by the spring on the presser h may be adjusted by causing the pin h' of the rod h^2 , to which the presser is attached, to engage one or the other of the longitudinal notches in the upper end of the hub d , or 75 by lifting the foot-piece e , which I have made of circular form and provided at opposite sides with projections 2, one of which is shown at Fig. 2, the other being just like and opposite to it, (see section, Fig. 3,) the said projections 80 entering notches made at the upper side of the bearing-ear h^4 . The upper bearing for the rod h^2 is marked h^3 . The legs n and heads $n' n^2$ of the flier are all as common. In the old form (represented in Fig. 5) the foot-piece c takes 85 but one bearing—that against the arm of the flier—and the strain exerted upon the spring by the movement of the presser acts to force the spring upward, and also against the rod within it, with which the presser is connected, 90 such strain, besides throwing the spring out of perpendicular position, causing friction between it and the rod, which prevents the free action of the spring when in use, which results in the making of uneven roving or yarn. In 95 this my invention the foot-piece having the spring connected with it, as described, and also being provided with two projections which enter recesses in the bearing h^4 , is prevented from tipping or twisting out of shape, so as to bear 100 against the rod, and consequently the tension and action of the spring upon the presser are

uniform from the empty to the full bobbin, which is of great importance.

I claim—

1. The flier-body, its presser, and the presser-rod having a pin, h' , combined with the notched hub d and the foot-piece e , having the projections 2, the spring having its end coils soldered in recesses in the said sleeve or hub and foot-piece, and the bearings $h^3 h^4$, all constructed and arranged substantially as described.

2. The flier-body, its presser, the rod h^2 , bearings for it, pin h' , and the notched hub having its lower end shaped to engage and hold

one end of the wire spring, combined with the 15 said spring and a foot provided with a downward projection, 2, to enter a corresponding recess in the bearing h^4 , the said foot being made as described, to sustain one coil of the spring, substantially as described. 20

In testimony whereof I have signed my name to this specification in the presence of two subscribing witnesses.

JOHN A. V. SMITH.
